UNITED STATES PATENT OFFICE.

JOHN E. WALSH, OF NEW YORK, N. Y.

TENT STRUCTURE.

SPECIFICATION forming part of Letters Patent No. 795,080, dated July 18, 1905.

Application filed November 26, 1904. Serial No. 234,377.

To all whom it may concern:

Be it known that I, JOHN E. WALSH, a citizen of the United States, and a resident of the city of New York, borough of Manhattan, in the county and State of New York, have invented 5 a new and Improved Tent Structure, of which the following is a full, clear, and exact description.

This invention relates to improvements in 10 tent structures, the object being to provide a tent having a framing the several members of which may be readily put together to form a strong and durable structure and that may be separated and packed in a comparatively small 15 space convenient for transportation or storage.

I may here state that a tent embodying my invention is particularly designed for military camps, field, hospitals, and, in fact, under 20 all conditions where temporary abodes are required.

I will describe a tent structure embodying my invention and then point out the novel features in the appended claims.

25 Reference is to be had to the accompanying drawings, forming a part of this specification, in which similar characters of reference indicate corresponding parts in all the figures.

Figure 1 is a perspective view of a tent structure embodying my invention. Fig. 2 is a 30 cross-section thereof. Fig. 3 is a longitudinal vertical section. Fig. 4 is a perspective view of the ceiling structure. Fig. 5 shows in perspective one of the end posts and parts connected thereto. Fig. 6 shows a bunk-framing that may be employed. Fig. 7 is a fragmentary view illustrating a roof-suspending device employed, and Fig. 8 is a fragmentary view showing a modification.

40 The structure comprises a base or flooring 1, which may be in separable sections, and extended upward from this flooring are end posts 2, which at their lower ends are seated in recesses formed in the flooring, so that they may 45 be readily removed or inserted. Arranged in the upper ends of the end posts 2 are rollers 3, over which a cable 4 extends. This cable forms practically the ridge of the tent-roof. The ends of the cable may be secured to cleats 50 5 on the posts 2.

Supported by the posts 2 at a short distance below the upper ends thereof is a ceiling consisting of a longitudinal beam 6 and cross end beams 7, the said cross-beams 7 being provided with recesses to receive the ceiling strips 55 or boards 8, which it will be understood are loosely placed in position—that is, no screws, nails, or dowels need be employed. The longitudinal beam 6 is provided with tenons 9 at its ends for engaging in channels 10, 60 formed in the end posts 2. As here shown, the side walls of these channels 10 are constructed of wooden strips 11, secured to said posts. These channels are also designed when deemed necessary to receive the edges 65 of partition-boards 12. It may be here stated that the tent may by means of the partition-boards be divided into any desired number of compartments. Also comprised in the ceiling structure is a center cross-beam 12^a, 70 provided with a channel to receive the upper ends of partition-boards 13, the lower ends of which engage in channels the side walls of which are formed of strips 14, secured to the flooring. The end walls of the structure consist of boards 15, the upper ends of which are 75 slidable in channels formed in the cross end beams 7, while the lower ends engage in channels the walls of which are formed by strips 16, attached to the flooring. As a means for 80 providing communication between the several compartments doorways are formed and provided with swinging doors 17.

Under certain conditions it may be necessary to brace the end posts 2. For this purpose I may employ braces consisting of adjustable sections 18, secured together by means of bolts, as indicated in Fig. 8. Additional compartments or rooms may be formed at the end or ends of the structure, and for this 85 purpose top beams 19 are extended outward from the posts 2 and connect at their outer ends to uprights 20, removably belted at their lower ends to the floor. These extensions when covered at the top and sides, as will be 90 hereinafter described, will serve as cooking-rooms or for other desired purposes. I may also use in connection with the structure a bunk consisting of uprights 21, connected by cross-bars 22, on which base-boards 23 for a 100

mattress or the like may rest. These uprights, or at least the corner uprights 21, are connected to strips in the ceiling by means of bolts 24 passing through hangers 25 into said 5 uprights, and the opposite side members of the bunk-frame are prevented from spreading by means of bars 26, having notches to receive the projected ends of the cross-bars 22. The main roof consists of a textile material 10 27—such, for instance, as duck or canvas—and this roofing is supported from the cable 4 by means of clips 28, through which the cable passes, the said clips being attached to the roof by means of bolts 29, which pass through 15 a ridge-piece 30, attached to the folded center of the roofing. By this arrangement the roof may be moved along the cable from either end when it is desired to form an opening. Normally, however, the ends of the roofing 20 27 are secured to extension-roofings 31, which are of substantially triangular form and extend outward to connection with the uprights 20. The canvas siding 32 extends along the front and rear and around the ends of the 25 structure, the side portions being removably engaged with lugs 33 on the edge of the flooring 1, and the upper edges are secured by means of buttons or other suitable fastening devices to the roof 27, and the end portions 30 of the sidings are secured by means of buttons or other suitable fastening devices to the extension-roofings 31. These fastening devices, as clearly indicated in Fig. 2, consist of headed lugs 34, attached to the outer ceiling- 35 strips 8.

To prevent the entrance of air at the junction of the roofing parts and the sidings, the said roofing parts are provided with flaps 35, which hang over the edges. As shown in the drawings, the sidings are provided with doorways and window-openings, and, if desired, window-openings may be formed in the roofing. The main roofing 27 at its ends is secured to buttons or the like on removable brace-beams 40 36, and the inner ends of the extension-roofings 31 are also secured to buttons 37 on said braces. It is obvious that a tent construction embodying my invention may be made of any desired size and divided into any number of 45 compartments, and as the framing is comparatively light it may when separated be packed in a small space and readily transported, and when the structure is put together it may be drawn from place to place in a field or camp, as 50 the flooring is provided with wheels 38.

It will be noted that the corner-posts of the bunk device are arranged in telescopic sec-

tions, and as the upper ends are hinged to the hangers 25 the bunk-frame may be swung upward to the ceiling, and therefore moved out 60 of the way.

Having thus described my invention, I claim as new and desire to secure by Letters Patent—

1. A tent structure comprising a flooring, end posts detachably connected to the flooring, recessed cross-beams on the posts, a ceiling consisting of a plurality of separable members having their ends loosely seated in the beam-recesses, and a textile covering. 65

2. A tent structure comprising a flooring 70 consisting of separable members, end posts detachably connected to the flooring, a ceiling consisting of separable members, supported by said posts and below the upper ends thereof, a cable passing over the upper ends 75 of the posts, and a fabric roofing supported by said cable.

3. A tent structure comprising a main frame, having end posts, cross-bars on said end posts provided with recesses, a ceiling consisting of strips of wood, the ends thereof being removably seated in the recesses, a channeled cross-bar with which the ceiling-strips engage, and partition-boards for engaging in 80 said channel. 85

4. In a tent structure, a frame comprising posts, rollers at the upper ends of said posts, a cable engaging with said rollers, means for fastening the ends of the cable, a textile roof-section having a ridge at the center fold, clips 90 through which the cable passes and bolts securing the clips to said ridge. 95

5. In a tent structure, a sectional flooring, end posts removably connected to said flooring, cross-beams on said end posts having recesses, a ceiling consisting of spaced members, the ends of which engage in said recesses, upper extension-beams from said end posts, posts supporting the outer ends of said beams, roofing-sections of textile material covering the 100 main portion and extensions and side and end pieces of textile material. 105

6. In a tent structure, a main frame, and a bunk-frame suspended from the ceiling of the main frame, the said bunk-frame having telescopic upright members. 110

In testimony whereof I have signed my name to this specification in the presence of two subscribing witnesses.

JOHN E. WALSH.
